UNITED STATES PATENT OFFICE.

ELMER E. GOODWIN, OF CLE ELUM, WASHINGTON.

WINDMILL ATTACHMENT.

No. 879,099.

Specification of Letters Patent.

Patented Feb. 11, 1908.

Application filed February 18, 1907. Serial No. 357,903.

To all whom it may concern:

Be it known that I, ELMER E. GOODWIN, a citizen of the United States, residing at Cle Elum, in the county of Kittitas and State of Washington, have invented certain new and useful Improvements in Windmill Attachments, of which the following is a specification, reference being had therein to the accompanying drawings.

10 This invention relates to single acting reciprocating devices for operating the pumps which are actuated by wind mills; and particularly to mechanism for transmitting the power to operate the same from the wind motor.

15 The object of the invention is the provision of inexpensive and efficient means whereby power may be conserved during the inoperative stroke and expended to do useful work 20 in the operative stroke, when the duty often-times exceeds the force of the wind which drives the apparatus.

25 With this end in view, the invention consists in the novel construction, adaptation and combination of devices as will be herein-after described and claimed.

30 In said drawings, Figure 1 is an elevation of a portion of a wind-mill tower showing portions of the wind-mill power transmission 35 devices to make my invention clearly understood, and an embodiment of my invention, partly in section. Fig. 2 is an elevation of the invention shown in a different position than in which it is illustrated in Fig. 1, with parts of the tower. Fig. 3 is a detached perspective view of the controller head.

40 The reference letter A designates the wheel arbor of a wind-mill which is journaled in boxes, such as B, on a rotatable frame C, and carries a crank-disk D. The crank pin d of said disk is connected by a pitman E with a vertical rod F which operates the pump bucket or plunger, not shown.

45 All of the aforesaid parts as well as the tower G are or may be, of ordinary or suitable construction.

50 According to my invention, I provide a bar-like controller head 5, hereinafter designated as the "head," which is, under ordinary conditions, slidably fitted to the rod F as in a centrally disposed cavity 5', and held upon the rod by a detachable cap 5" secured with screw bolts 5", or otherwise.

55 Adjacent of the extremities of the head are notches 6 whereto are engaged the lower

ends of extensible springs 7 having their other ends engaged in hooks 8 which are adjustably secured in the platform g of the tower. Such adjustment of the hooks are desirably had by providing screw threads 60 upon the shanks 8' of the hooks to register with the threads of butter-fly nuts 8" seated upon washers 8''' upon the top of said platform.

65 Adjustably secured to the rod F so as to engage, during the down stroke, with the head, is a set collar 9, and by means of which the head is carried against the opposing force of the springs while the power thus absorbed is asserted, supplementary to the 70 power exerted by the wind - mill, to accomplish the return upward stroke of the rod together with its load. To facilitate the aforesaid actions in a more even manner I provide devices to interrupt the movement 75 of the head a short distance before the rod reaches the end of its upward travel, that is to say, when the speed thereof is being retarded by traverse movement of the crankpin prior to the latter's passing its neutral 80 axis or "dead center," and thence be disengaged until the momentum of the driving parts is sufficient to overcome the resistant force of the springs. Specifically such functions are attained by employing screw 85 threaded bolts 10 which are extended through screw threaded apertures 11 of the head and are arranged to impinge against bumper blocks 12 secured to the tower. The bolts 10 are desirably formed with wings 10' 90 whereby they are readily turned for regulating their positions and are thereupon reliably held by lock-nuts 10. The bolts 10--10 will be found of great efficiency and utility especially when the wind is irregular. 95

The operation of the invention, it is thought, will be understood from the foregoing and its advantages are believed to be obvious.

Having described my invention, what I 100 claim as new and desire to secure by Letters-Patent, is—

1. The combination with a supporting structure, of a vertical rod, means carried by said structure for reciprocating said rod, a head member through which said rod is movably disposed, a stop carried by said rod and adapted to engage said head, springs connecting said head yieldably to said supporting structure, and threaded adjusting 105 110

rods carried by said head and adapted to bear against said supporting structure when said springs are fully collapsed.

2. In apparatus of the class described, the combination with a wind-mill arbor, a tower, a vertically arranged rod, a collar upon said rod, and operative connection between said arbor and rod whereby the latter is reciprocated, of a head slidably mounted upon said rod, springs connecting the head with said tower and tending to exert an upward pressure of the head against said collar, means to

adjust the tension of said springs, bolts adjustably connected with said head, and bumpers adapted to be impinged by said bolts and release the collar from the pressure exerted thereupon from said head. 15

In testimony whereof I affix my signature in presence of two witnesses.

ELMER E. GOODWIN.
